[57] CLAIM

The ornamental design for a baby carriage, as shown and described.

DESCRIPTION

FIG. 1 is a side perspective view of a baby carriage showing my new design;

FIG. 2 is a top plan view thereof;

FIG. 3 is a perspective view thereof taken from the left of FIG. 1; and

FIG. 4 is a perspective view thereof taken from the right of FIG. 1.

The side opposite that shown in FIGS. 1 and 4 is substantially a mirror image thereof, the only difference being that the opposite side does not include the brake mechanism which is shown in conjunction with the right rear wheel set of the carriage.

FIG. 1.

FIG. 2.

FIG. 3.

FIG. 4.
